CLAIM

I claim the ornamental design for a set of components for upgrading a lock, as shown and described.

DESCRIPTION

FIG. 1 is a top, front, left perspective view of a set of components for upgrading a lock showing my new design; FIG. 2 is a bottom, rear, left perspective view thereof; FIG. 3 is a bottom, Front, right perspective view of the first component of the upgrading lock;

FIG. 4 is a top plan view of FIG. 3;

FIG. 5 is a bottom plan view of FIG. 3;

FIG. 6 is a rear elevational view of FIG. 3;

FIG. 7 is a front elevational view of FIG. 3;

FIG. 8 is a left side elevational view of FIG. 3;

FIG. 9 is a perspective view of a second component of the upgrading lock;

FIG. 10 is a top plan view of FIG. 9;

FIG. 11 is a bottom plan view of FIG. 9;

FIG. 12 is a front elevational view of FIG. 9, the rear elevational view being a mirror image thereof;

FIG. 13 is a perspective view of a third component of the upgrading lock;

FIG. 14 is a top plan view of FIG. 13;

FIG. 15 is a bottom plan view of FIG. 13;

FIG. 16 is a rear elevational view of FIG. 13;

FIG. 17 is a front elevational view of FIG. 13;

FIG. 18 is a left side elevational view of FIG. 13, the right side elevational view being a mirror image thereof;

FIG. 19 is a perspective view of a fourth component of the upgrading lock;

FIG. 20 is a top plan view of FIG. 19;

FIG. 21 is a bottom plan view of FIG. 19;

FIG. 22 is a rear elevational view of FIG. 19;

FIG. 23 is a front elevational view of FIG. 19; and,

FIG. 24 is a left side elevational view of FIG. 19, the right side elevational view being a mirror image thereof.

The broken lines illustrate unclaimed portions and form no part of the claimed design.

Any portions of the components of the set not shown form no part of the claimed design.

1 Claim, 6 Drawing Sheets
